DESIGN FOR A DESK MICROPHONE

Robert L. Stone, Guilford, Conn., assignor to The Soundscriber Corporation, New Haven, Conn., a corporation of Connecticut

Application June 5, 1945, Serial No. 119,913

Term of patent 14 years

(Cl. D56—4)

To all whom it may concern:

Be it known that I, Robert L. Stone, a citizen of the United States, residing in the town of Guilford, county of New Haven, and State of Connecticut, have invented a new, original, and ornamental Design for Desk Microphone, of which the following is a specification, reference being had to the accompanying drawing, forming a part thereof.

Fig. 1 is a side elevational view of the desk microphone showing my new design.

Fig. 2 is a top plan view of the same.

Fig. 3 is a front elevational view of the same.

Fig. 4 is a rear elevational view of the same.

I claim:

The ornamental design for a desk microphone, as shown.

ROBERT L. STONE.
